US00D987832S

(12) **United States Design Patent** (10) **Patent No.:** **US D987,832 S**
(45) **Date of Patent:** **** May 30, 2023**

(54) **PNEUMATIC COMPRESSION DEVICE**

(71) Applicant: **Therabody, Inc.**, Los Angeles, CA (US)

(72) Inventors: **Jaime Sanchez Solana**, Los Angeles, CA (US); **Brian Carberry**, Beverly Hills, CA (US); **Brian Zeng**, Dongguan (CN); **Washington Alexander Silva Garces**, Los Angeles, CA (US); **William Webb**, San Francisco, CA (US); **Patrick Tufts**, San Francisco, CA (US); **Cale Kaufman**, Oakland, CA (US)

(73) Assignee: **Therabody, Inc.**, Los Angeles, CA (US)

(**) Term: **15 Years**

(21) Appl. No.: **29/821,801**

(22) Filed: **Jan. 3, 2022**

(51) LOC (14) Cl. **24-02**

(52) U.S. Cl.

USPC **D24/190**; D24/200

(58) **Field of Classification Search**

(57) **CLAIM**

The ornamental design for a pneumatic compression device, as shown and described.

DESCRIPTION

FIG. 1 is a perspective view of a pneumatic compression device showing the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the figures show portions of the pneumatic compression device that form no part of the claimed design.

1 Claim, 6 Drawing Sheets
